UNITED STATES PATENT OFFICE.

BERNARD FAY, OF DANBURY, CONNECTICUT.

SAFETY APPLIANCE FOR RAILROAD BLOCK SYSTEMS.

Application filed August 18, 1921. Serial No. 493,290.

To all whom it may concern:

Be it known that I, BERNARD FAY, a citizen of the United States, residing at the city of Danbury, in the county of Fairfield 5 and State of Connecticut, have invented certain new and useful Improvements in Safety Appliances for Railroad Block Systems; and I do declare the following to be a full, clear, and exact description of the 10 invention, such as will enable others skilled in the art to which it appertains to make and use the same.

This invention relates to certain new and useful improvements in a safety appliance 15 for railroad block systems, and more especially to an electric or trolley railroad having a main trolley wire or rail of the overhead type, underground type or the third rail type.

20 The primary object is to provide a safety appliance which will be efficient, practical and reliable in operation as well as one for bringing a train or cab to rest in the usual gradual manner.

25 The invention further has for an object to provide a safety appliance adapted to be introduced or connected to the brake system equipment which will apply the brakes in much the same manner as when under the 30 control of an engineer or motorman.

The invention also resides in the provision of a valve actuating mechanism for automatically setting the brakes, and a fluid motor for operating said mechanism according 35 to a predetermined but variable movement to effect the gradual application of the brakes.

The invention also resides in a safety appliance and a block system, the latter embodying auxiliary side or block wires paralleling succeeding lengths of a main trolley wire on opposite sides thereof, thereby dividing said block wires into forward and rearward sections, each section being an inherent 45 dead wire and adapted to be brought into circuit with the main trolley wire when the sections are occupied by two succeeding cabs or trains.

Further the invention resides in an improved 50 block system having block trolley wires paralleling a main trolley wire for successive lengths thereof and on opposite sides, that section of the main trolley wire which is paralleled on one side by a section

of a block trolley wire being paralleled on 55 its opposite side by a section of a succeeding block trolley wire so that in effect the main trolley wire will be paralleled throughout its length and on opposite sides by sections of successive block trolley wires which 60 are separated from each other by comparatively short lengths of insulation.

The invention will also be found to reside in the features of construction and the arrangements and combinations of parts hereinafter described and claimed, reference being had to the accompanying drawings, wherein:

Figure 1 is a schematic view of the improved railroad block system; 70

Figure 2 is a diagrammatic view of a cab equipped with the trolleys and safety appliance, the latter not being shown;

Figure 3 is a detailed section through a trolley wire support as on line 3—3 of Figure 1, depicting the short piece of insulation between two block trolley wire sections; 75

Figures 4 and 4^a are a diagrammatic view of the improved emergency braking mechanism with the parts arranged in their normal 80 position;

Figure 5 is a vertical transverse section thereof taken through the cam slide support; and

Figure 6 is a detail section on line 6—6 of Figure 5. 85

Referring more in detail to the accompanying drawing, the schematic or diagrammatic showing in Figure 1 embodies a main feed or trolley wire 1 suspended at intervals 90 by transverse supports 2 which are mounted on poles 3 in an obvious manner. Separate auxiliary or block trolley wires 4, 5, 6, 7 and 8 parallel the main wire 1, each block trolley wire beginning at a support 2 on one 95 side of the main feed wire and extending parallel thereto for a distance of say one mile and then crosses the main trolley wire on an adjacent support 2 to the opposite side and extends in the same direction and parallel to the main trolley wire for a predetermined distance. The next trolley wire, for instance wire 6, commences at the cross-over support 2 of wire 5 and extends parallel to the latter or second section of said former 100 wire, a distance equal to the length of said section, and then crosses over the main trolley wire and extends a predetermined dis-

tance on the opposite side thereof, terminating at a third support. The succeeding block trolley wire 7 commences at the cross-over support for wire 6, extends parallel to 5 the main trolley wire on the opposite side from the rear or second section of said block wire 6, crosses over the main trolley wire on said third support and then extends parallel to the main wire. This arrangement of the 10 block trolley wires continues throughout the track system, the front section of one block wire overlapping the rear section of the next preceding block wire and the rear section of the former block wire overlapping the front 15 section of the next succeeding block wire so that throughout the length of the track the main trolley wire is paralleled on both sides by the block wires, the block wire on one side being in a different block from the wire on 20 the opposite side. The block wire sections on the same side of the main wire are in substantial alignment with each other and the intervening space on the support is filled with insulation 9 so as to present an uninterrupted path for a trolley and thereby minimize the possibility of the trolley jumping 25 the wire.

A trolley is provided for each wire making three in all indicated by the numerals 30 10, 11 and 12. These trolleys are carried on a car or cab such as is designated by numerals 13 and 14, the trolleys 10 and 11 being electrically connected as indicated at 35 15 and trolley 12 being connected in series with a magnet 16 which forms a part of the brake-applying mechanism carried by the cab or train.

The brake system embodies a feed pipe 17 leading from a main reservoir containing 40 air under pressure to the engineer's valve 18 from which leads a pipe 19 to the brake cylinders (not shown), it being understood that when compressed air is admitted to the brake line the brakes will become inoperative or free and when the compressed 45 air is let out of the brake line the brakes will become operative or set, such admission and exhaustion being under the control of the engineer's valve.

50 In addition to the foregoing braking system, the following mechanism is also carried by the cab or train and consists broadly of an air motor, a valve actuating mechanism operable thereby for effecting a slow 55 application of the brakes on the train or cab, and a series or plurality of valves under the control of the magnet 16 for admitting air pressure to operate the air motor.

The air motor consists of a cylinder 20 60 having an exhaust pipe 21, 22 at each end and a pressure supply pipe 23, 24 connecting the main reservoir or pipe 17 to each end of said cylinder. A piston 25 operates within the cylinder and has its piston rod 26 65 pivotally connected to a cam slide member

27, the latter being slidably guided in a stationary bracket or support 28. This cam slide support or bracket is U-shaped in cross section or it may be considered as a rectangular box having one side open and its 70 upper and lower arms formed with opposing grooves 29 in which the tongues 30 of the cam slide have sliding fit.

Located in proximity to each other is a series of valves 31, 32, 33, 34, and 35 having manipulating levers 36 all pivotally connected with a common bar 37 which in turn has one end linked to the armature or core 38 of magnet 16. The opposite end of the bar 37 has a coil spring 39 connected thereto for being placed under tension when the magnet attracts its core so as to return said bar to its normal position when the magnet again becomes deenergized. The valve 35 is placed in a pipe 40 which connects the engineer's valve to a pipe 41 leading from the brake line 19. This emergency exhaust pipe 41 is provided with a normally closed valve 42 adjacent the path of travel of the cam slide 27 and beyond the point of connection with pipe 40. Pipe 23 is provided with a valve 43 in proximity to the path of travel of the cam slide, and in a like manner pipe 24 is provided with a valve 44 the latter having an operating handle 45 equipped with a pin 46 for engaging in a notch or recess 47 provided in the upper end of an arm or plate 48 attached to the cam slide.

The cam slide consists of a rectangular frame divided by a longitudinal frame member or support 49 which is equipped on its upper face with inner and outer pairs of cams arranged in forward and rearward pairs and designated by numerals 50, 51, 52 and 53. The bottom frame member is similarly equipped with pairs of cam lugs 54, 55, 56 and 57. The top frame member is provided with a depending cam projection 58 and the intermediate frame member is provided with a pair of such projections 59 and 60. The valves 42 and 43 have their valve stems extending above the path of movement of the cam lugs 50 to 57, inclusive, and each stem is equipped with a fixed bell crank lever and a freely suspended lever 61, the latter being arranged to gravitate into the path of the outer lugs 50, 51 and 54, 55, respectively, while the inner pairs of lugs are designed to engage lever arms 62 of the bell crank levers, the opposite arms carrying lateral pins 63 to be engaged by the levers 61. It will be noted that the upper pairs of cam lugs are arranged slightly in advance of the corresponding pairs of lower lugs, and that the depending cam projections 58 and 59 are disposed slightly offset and between the front and rear pairs of cam lugs, all of the cam lugs and projections being arranged at the forward end 115 120 125 130

of the cam slide frame with the exception of the depending cam projection 60 which is located towards the rear end.

Figures 4 and 4^a depict the mechanism in its normal position wherein valves 32, 34, 35 and 43 are opened and valves 31, 33, 42 and 44 are closed. Assuming that the car 14 is in block 6-7 and that car 13 has just entered the succeeding block 5-6, as illustrated in Figure 1. The wire 7, being dead, will have no influence on the magnet 16 of the front car 14. However the electrically connected trolleys 10 and 11 on the front car will conduct the current from the main trolley wire 1 to the block trolley wire 6 from which the current will pass through the rear trolley 12 to magnet 16, energizing the same, and completing the circuit through a ground back to the main trolley wire. Being thus energized, the magnet 16 will attract its armature or core 38 and thereby pull the bar 37 against the tension of spring 39 and effect a reversal of the valves 31 to 35 inclusive, or in other words the valves 31 and 33 will be opened and the valves 32, 34 and 35 will be closed.

As a result of this movement or operation compressed air will be admitted from the supply pipe 17 through the now opened valve 31 and the normally opened valve 43 into the rear end of the cylinder 20 behind the piston 25 thereby moving the latter forwardly or toward the opposite end while the fluid in advance thereof will escape through exhaust pipe 22. Movement of the piston will pull the cam slide 27 to the right, in Figure 4 with the following action by the cam lugs and projections, lugs 53 and 57 will ride from under arm 62 and immediately lugs 51 and 55 will successively wipe past levers 61 which, through pins 63, will throw the arms 64 up into the paths of the cam projections 58 and 59, such movement of the valves fully opening the exhaust pipe 41 and partially closing pipe 23 so that the speed of the piston will be lowered for the initial setting of the brakes. Immediately following this the cam projections 59 and 58 wipe the respective arm 64 to return the valves 42 and 43 to their normal fully closed and fully opened positions respectively. This temporarily restrains a firmer setting or application of the brakes and speeds up the movement of the piston until the latter is again retarded by the partial closing of valve 43 by lug 50 engaging lever 61 and the brakes are more firmly set by the lug 54 engaging lever 61 to finally bring the train or car to a stop, the cam slide continuing its slow or gradual advance so that cam projection 60 will engage the upwardly disposed arm 64 and return the valve 42 to its normally closed position. In the meantime the arm 48 has pulled the valve lever 45 forwardly to open the valve 44.

After the first cab 14 has moved out of block 6-7 the circuit which includes the magnet 16 will be broken or interrupted by reason of the front trolley 10 having passed from the block wire 6. Therefore, the magnet will become deenergized and the spring 39 will be free to pull the bar 37 to the left, or to the position indicated in Figure 4 wherein the valves 32, 34 and 35 will be opened and the valves 31 and 33 closed. The air pressure will have therefore been shut off from the rear end of the cylinder and opened or admitted to the front end thereof since both valves 32 and 44 will be opened. Likewise the exhaust to the rear of the cylinder will be opened while that to the front end will be closed. Fluid pressure acting on the front side of the piston will drive the latter rearwardly and consequently shift the cam slide in a similar direction. The valve 42 having previously been shut by cam projection 60, will be unaffected by the rearwardly moving cams 54, 55, 56, 57 and 59, the outer cams 54 and 55 merely wiping beneath the freely pivoted lever 61 while the other cams pass by the valve without moving any part. In a like manner the outer cams 50 and 51 will wipe the freely pivoted upper lever 61 without affecting the valve 43 while the cam 52 will engage arm 62 to move the partially closed valve 43 to its fully opened position. In their normal position the cams 53 and 57 rest directly beneath the arms 62 and serve as safety devices or stops to prevent unauthorized movement of the valves. A projecting portion of plate 48 then engages the valve pin 46 and swings the lever 45 to shut the valve 44 thereby closing the front end of the cylinder to the fluid pressure supply.

The valve 35 is placed in the pipe line 40 for supplying a small amount of air to the brake line in case of leakage.

It will be noted that one function of the cam slide is to slowly bring the cab or train to a stop which is accomplished by the alternate opening and closing of the exhaust valve 42. The cam slide also serves to finally close the exhaust valve to thereby place the brake system in condition for again being under the control of the engineer, this occurring after the brakes have been effectively applied by the safety mechanism. The emergency fluid pressure pipes 23 and 24 are also under the control, to a limited extent, of the cam slide.

It will be obvious that the side or block wires are dead normally and are only brought into play when two trains are within two adjacent blocks and that as soon as the forward train leaves its block the block wires again become dead or functionless.

It will thus be apparent that the herein described block system will operate as a

certainty and the cab or train will have its motion arrested gradually rather than in an abrupt manner. It will also be noted that the safety appliance with which the cab is equipped is a simple construction and brings the usual brake equipment into play in an ordinary manner.

What is claimed is:

- 10 1. A trolley car for railroad block systems, having an air brake system, auxiliary means for automatically operating the brake system comprising an operating cylinder connected by a pipe to the air line of the brake system, a normally closed valve in said pipe, electrical means for opening the valve when the trolley car runs into an occupied block, an exhaust valve for the system normally shut, an air-actuated piston in the cylinder, and means operable by a single 15 movement of the piston for intermittently opening the exhaust valve to bring the car to a gradual stop.
- 20 2. A trolley car for railroad block systems, having an air brake system, auxiliary means for automatically operating the brake system comprising an operating cylinder connected by a pipe to the air line of the brake system, a normally closed valve in said pipe, electrical means for opening the 25 valve when the trolley car runs into an occupied block, an exhaust pipe and valve for the system normally shut, a pipe connection between the pipe line and the exhaust pipe at a point in advance of the exhaust valve, a normally open valve in the pipe connection, means operating to close the latter 30 valve and open the exhaust valve, and a fluid actuated piston in the cylinder for operating said exhaust valve operating means.
- 35 3. A trolley car for railroad block systems, having an air brake system, auxiliary means for automatically operating the brake system comprising an operating cylinder connected by a pipe to the air line of the brake system, a normally closed valve in said pipe, means for opening the valve when the trolley car runs into an occupied block, a second 40 valve in said pipe normally open, an exhaust valve for the brake system, a piston operable in the cylinder, and means operable by the piston for simultaneously opening the exhaust valve and partially closing said second valve.
- 45 4. A safety appliance for railroad block system, comprising a cylinder, an exhaust valve for each end thereof, a pair of pipes connecting the opposite ends of the cylinder to the usual fluid pressure supply of the 45 system, a valve in each of said pipes one of which is normally opened and the other normally closed, a normally open valve in the pipe having the normally closed valve, a piston operable in the cylinder, an exhaust 60 valve for the brake system, and means oper-

able by the piston for partially closing said second normally opened valve and for fully opening said last named exhaust valve.

5. A safety appliance for railroad block system comprising an air motor, pipe for connecting the motor to the air supply of the usual braking system, a valve in said pipe normally open, an exhaust valve for connection with the brake system and being normally closed, and means operable by the motor for alternately partially closing and opening the first valve to retard and increase the action of the motor and for simultaneously alternately opening and closing the exhaust valve. 80

6. A safety appliance for railroad block system comprising an air motor, a pipe for connecting the motor to the air supply of the usual braking system, a valve in said pipe normally open, an exhaust valve for connection with the brake system and being normally closed, a slide operable by the motor and having longitudinally spaced cam lugs for effecting successive operations of the two valves and cam projections interposed between the longitudinally spaced lugs for returning the valves to their normal position, and means for reversing the direction of travel of the slide. 90

7. A safety appliance for railroad block systems comprising an air motor, a pair of pipes connecting the motor to the air supply of the usual braking system for effecting forward and reverse running of the motor, a normally open valve in one pipe and a normally closed valve in the other pipe, the latter pipe also containing a normally open valve, means operable upon a car entering an unauthorized block to reverse the positions of the first two valves to thereby start the 100 motor, means operable by the motor to effect a reduction in pressure in the brake system and for controlling said third valve to thereby govern the action of the motor, and means operable by the first means and the second 105 means for reversing the operation of the motor.

8. In a safety appliance for railroad block systems, a brake system exhaust valve, an actuator therefor to successively open and close the valve, and means under the control of the actuator for operating the latter. 115

9. In a safety appliance for railroad block systems, a brake system exhaust valve, an actuator therefor to successively open and close the valve, an air motor for operating the actuator, and means under the control of the actuator for varying the speed of the motor. 120

10. In a safety appliance for railroad block systems, a brake system exhaust valve, an actuator therefor to successively open and close the valve, an air motor for operating the actuator, a valve for controlling the supply of fluid pressure to the motor for driv- 125 130

ing it in one direction, means under the control of the actuator for operating the valve to vary the supply during movement of the actuator, and means operable by the actuator 5 for reversing the movement of the motor.

11. An air brake system embodying an air line, an exhaust valve, a fluid motor for actuating the valve, a pipe connecting the air line to the motor, and means for controlling 10 the communication between the air line and the motor to initially accelerate and then diminish the action of the latter.

12. An air brake system embodying an air line, an exhaust valve, an actuator movable 15 to successively open and close the valve, means for moving the actuator, and means under the control of the actuator for controlling the first means.

13. An air brake system comprising an air line, an exhaust valve therein, a reciprocating fluid motor for opening, closing and opening the valve during one cycle of movement and electro-responsive means for establishing communication between the motor 25 and the air line to effect operation of the motor.

14. An air brake system comprising an air line, a valve therein having a stem, a bell crank lever fixed on the stem, an arm freely pivoted on the stem and adapted to engage 30 a lateral projection from the lever to actuate the valve, and an actuator slide carrying a cam lug for normally engaging one end of the lever to positively hold the valve in one position and a second cam lug for wiping the 35 arm to effect movement of the valve from said position when the first lug has passed from engagement with said lever.

15. An air brake system comprising an air line, an exhaust valve therein, a movable 40 actuator for controlling the valve, a fluid motor for operating the actuator, conduits connecting the air line to the motor and embodying oppositely positioned valves for controlling the forward and reversed running 45 of the motor, said valves being controlled by the actuator, and electro-responsive means for starting the operation of the motor.

In testimony whereof I affix my signature 50 hereto.

BERNARD FAY.
